UNITED STATES PATENT OFFICE.

JOSEPH F. MONTINE, OF NEVINVILLE, IOWA.

COLLECTION AND DELIVERY APPARATUS.

1,132,863.

Specification of Letters Patent.

Patented Mar. 23, 1915.

Application filed February 1, 1915. Serial No. 5,472.

To all whom it may concern:

Be it known that I, JOSEPH F. MONTINE, a citizen of the United States, residing at Nevinville, in the county of Adams and State of Iowa, have invented certain new and useful Improvements in Collection and Delivery Apparatus, of which the following is a specification.

This invention relates to apparatus for collecting and delivering mail and other receptacles along a route, and its object is to provide a novel and improved apparatus of this kind characterized by an overhead track or cableway on which is mounted a car which carries the receptacles to be delivered at the different stations along the route, and also picks up a receptacle at each station, this delivery and collection of receptacles being automatically effected.

The herein stated object is attained by means of a novel combination and arrangement of parts to be hereinafter described and claimed, reference being had to the accompanying drawings in which—

Figure 1 is a side elevation of the apparatus; Fig. 2 is a plan view of the car, partly broken away and in section; Fig. 3 is a rear end view of the car; Fig. 4 is a section on the line 4—4 of Fig. 2; Fig. 5 is a section on the line 5—5 of Fig. 4; Fig. 6 is a section on the line 6—6 of Fig. 2; Fig. 7 is a plan view of the receiving apparatus at a station; Fig. 8 is an inverted plan view of said apparatus; Fig. 9 is a section on the line 9—9 of Fig. 4, and Fig. 10 is a section on the line 10—10 of Fig. 9.

In carrying out the invention, there is provided a car having a middle compartment 15, and a side compartment on each side, said side compartments being indicated at 16 and 17, respectively. The side compartments are longer than the middle compartment and extend forward beyond the ends of the latter. The middle compartment is closed at its ends, and the side compartments are open at their ends, the side walls at the front end being flared as indicated at 18. The side compartments are designed to carry the receptacles containing the mail or other goods, said receptacles being hung in a row in the compartments as will be presently described, the flared ends 18 facilitating the entry of the receptacles. The middle compartment contains a mechanism, to be presently described, for releasing the receptacles, one after the other.

The roofs of the side compartments 16 and 17 are arched, and each roof has a longitudinal slit 19, over which is mounted a housing 20. At the front end of each compartment its housing 20 has outstanding side flanges 21 to which is secured a platform 23 which extends forwardly of the compartment at the top thereof and has a longitudinal slit or passageway 24 forming a continuation of the slit 19, said slit 24 continuing to the forward end of the platform and being flared at said end as indicated at 25. The platform has upstanding marginal flanges 26 forming continuations of the roof of the compartment, and tapered at their forward ends as indicated at 27. The platforms of the respective compartments 16 and 17 are connected by a cross brace 28.

The slits 19 and 24 are designed to form a runway for the mail or other receptacles. Each of these receptacles is a cylindrical body 29 having a domed top, and a removable bottom 30 in the form of a screw cap, said cap having corrugations 31 for a purpose to be presently described. To the top of the receptacle is secured an upstanding bracket member 32 carrying rollers 33 arranged in pairs, one in front of the other. The ends of the bracket member have reinforcing lugs 34.

The car takes on a receptacle 29 at the front end, the bracket member 32 entering the slit 24 and the rollers 33 mounting the platform 23. The receptacle then passes into the side compartment 16 or 17, the bracket member passing along the slit 19 and the rollers traveling along the top of the compartment roof in the housing 20, said roof having grooves 35 on opposite sides of the slit 19 forming tracks for the rollers. These grooves start at the front end of the compartment and terminate a short distance from the rear end thereof. The housing 20 also does not extend rearward beyond the grooves.

On the inner face of the top of the housing 20 is mounted a row of pivoted dogs 36 depending therefrom, and so mounted that they are prevented from dropping to perpendicular position. In the upper edge of the bracket member 32 are two sets of ratchet teeth 37 and 38 respectively, inclined in opposite directions. One of the dogs 36 is designed to engage one of the sets of ratchet teeth to prevent the receptacle 29 from backing out of the compartment 16 or

17. Two sets of oppositely inclined ratchet teeth are provided so that the dogs will operate with either edge of the incoming bracket member. The number of dogs corresponds to the number of receptacles the compartment is capable of holding, a locking dog being provided for each receptacle, and the dogs being spaced to correspond to the spacing of the receptacles in the compartment.

18. At each station where a receptacle 29 is to be collected or picked up, is mounted a rectangular box like structure 39 having open ends and a bottom slit 40, the receptacle being placed in said box to await collection. The front end of the box is flared as indicated at 41 to facilitate the entry of the receptacle. The box is supported, at such an elevation that it is a short distance above the housing 20, by means of a bracket arm 42 carried by a pole 43 and having upturned marginal flanges 44. The top of the box has a slight downward taper at the rear end as shown at 45, for the reason that as the car approaches and the platform 23 moves under the box, the slit 24 of the latter will take the bracket member 32 of the waiting receptacle, and as soon as the front edge of the housing 20 strikes the edge of said bracket member, the receptacle will begin to move with the car and will drop onto the platform as soon as it issues from the rear or farther end of the box 39. However, as the receptacle is struck, it might tip back and lodge in the box; but this is prevented by the slant 45, the latter preventing the receptacle from rising in the box. The connections 46 of the box with the bracket arm 42 are slotted as indicated at 47 to permit slight side play of the box.

19. Assuming that the compartment 16 is filled with receptacles 29, and that another receptacle has been picked up and is hanging from the platform 23, a means is provided whereby this receptacle is drawn into the compartment from the front after the rearmost receptacle in said compartment has been left at a station. It will be noted that the housing does not reach to the rear end of the compartment, which leaves the bracket member 32 and the rollers 33 of the rearmost receptacle exposed, so that if said receptacle should be moved back out of the compartment, its bracket member 32 will strike one of the branches 48 of a bell crank lever fulcrumed at 49 on the roof of the compartment and having connected to its other branch a rod 50. This rod extends longitudinally over the roof of the compartment, and about midway between the ends has an abutment 51 against which bears one end of a coiled spring 52, the other end of said spring abutting against a lug 53 fast on the compartment roof. This spring opposes the forward movement of the rod. On the

20. roof of the middle compartment 15 is mounted a bearing 54 which supports a transverse rock shaft 55 having rocker arms 56 and 57, respectively, at its ends. The rocker arm 56 has an eye through which the 70 forward end of the rod 50 slidably passes, there being a head or abutment 58 on said end of the rod. The part 58 is on one side of the rocker arm 56, and on the other side of the latter, the rod has an abutment 59. 75 A light coiled spring 60 is mounted on the rod between the rocker arm 56 and the abutment 59. Thus a yielding connection between the rod 50 and the rocker arm 56 is provided, the motion of the former being 80 transmitted to the latter by the spring 60. The rocker arm 57 extends down into the compartment 15 through a slot in the roof thereof in the same direction as the rocker arm 56. As the arm 57 is fast on the shaft 85 55, it swings when the shaft is rocked through the rod 50 and the arm 56. When the arm 57 swings down it drops into the jaws of a knife switch 61 and closes the circuit of an electric motor 62 mounted on a 90 suitable base 63 in the compartment 15. This motor is set with a shaft 64 running longitudinally of the car, and on said shaft is a worm 65 which is in mesh with a worm wheel 66 the shaft 67 of which is suitably 95 supported in the compartment 15. The shaft 67 carries an outstanding spring finger 68 which is in the path of the rocker arm 57, and at each revolution of the wheel 66 said spring finger strikes said rocker arm and 100 swings the same in a direction to clear the switch jaws 61, and thus open the circuit of the motor 62. A spring 69 coiled around the rock shaft 55 holds the same so that it will not turn and allow the rocker arm 57 105 to drop by gravity into position to close the switch. The worm wheel 66 has a wrist pin 70 to which is connected a pitman 71 which extends forwardly of the car and passes out of the compartment 15 through a 110 slit 72 in the front wall thereof, and in front of said compartment, the pitman has two converging branches 73 which are pivotally connected, as indicated at 74, to a transverse 115 pusher bar 75 of sufficient length to come with its ends adjacent to the slits 24 of the platforms 23, the cross bar being normally positioned at the forward ends of said slits. The inner marginal flanges 26 of the platform have slots 76 through which the bar 75 120 slidably passes. On each end of the bar 75 is mounted a pivoted dog 77 which is swung to normal outward position by a bow spring 78. The dogs prevent the exit of the receptacles 29 from the platform slits 24, 125 but yield to allow the receptacles to enter. The dogs are not in the way of the rollers 33 as the latter will not have descended to the platform at this point. When the pitman 71 is drawn back by the worm wheel 66, the 130

cross bar 75 is also retracted, and a receptacle hanging from the platform will be pushed under the housing 20 and into the compartment beneath the same by the dog 5 77. The reciprocatory motion of the cross bar is guided by rollers 79 running along the inner marginal flanges 26 of the platform. It will be seen from the foregoing that the outgoing rear receptacle 29, through the 10 elements 48 to 79, causes the receptacle last taken up to be pushed into the car, the latter receptacle pushing back the remaining receptacles in the car to again fill the same, the rearmost one coming into position close 15 to the rear end of the car and taking the place of the one just discharged.

For delivering the outgoing receptacle 29 to the receiving apparatus at the station, the following mechanism is provided: To the 20 cross bar 75 are connected two rearwardly extending rods 80, one for each of the compartments 16 and 17. These rods may be connected to knuckle plates 81 secured to the cross bar, said plates serving as the 25 pivotal connection of the pitman branches 73 with the cross bar. The rods 80 pass into the middle compartment 15 through long slots 81^a in the front wall thereof and they extend along the side walls of said compartment. The rear ends of the rods are headed as indicated at 82, and provided with an abutment 83. Between the head and the abutment of each rod, the latter carries light and heavy coiled springs 84 30 and 85, respectively. Between these two springs is located the outer end of a rocker arm 86 which is fast on a sleeve 87 held against longitudinal movement by a bearing plate 88 mounted on the wall of the compartment. The rocker arm has an eye 40 through which the rod loosely passes, and the springs 84 and 85 provide a yielding connection between said arm and the rod. The sleeve 87 is mounted on a stationary 45 shaft 89 on which it is free to rock. The shaft 89 extends transversely of the middle compartment 15 and passes at its respective ends into the side compartments 16 and 17. The sleeve 87 also has a fixed arm 90 extending therefrom at an angle to the arm 50 86. The parts 86, 87 and 90 therefore form a bell-crank lever, the branch 86 being vertical, and the branch 90 being horizontal. Each end of the shaft carries one of these 55 bell-crank levers to the branches 86 of which the rods 80 are connected, respectively, as hereinbefore described. The sleeve or hub portions 87 of the bell-crank levers are so positioned that the branch 90 of one of said 60 levers is located in the compartment 16 and the branch 90 of the other lever in the compartment 17. Each branch 90 is normally positioned horizontally beneath the 65 row of receptacles 29 on the longitudinal center line thereof, and it extends back as

far as the center of the rearmost receptacle. The rear or outer end of the branch 90 has an upward bend 91 at the top of which is an arcuate enlargement 92 provided intermediate its ends with a sleeve member 93 projecting from opposite sides of said part 92. Through this sleeve member passes a pin 94 which supports a horizontal plate 95, the latter having depending ears 96 at the bottom to receive the ends of the pin. The 70 plate 95 is thus supported at the center so that it may rock slightly about the pin 94, in the direction the branch 90 extends, this rocking movement being limited by the part 75 92. The plate 95 has a forward extension 80 97 which terminates in a concave downward flange 98. A weak spring 99 connects this flange with the bend 91 of the arm or branch 90 of the bell-crank lever, so that the forward end of the plate 95 has a tendency to 35 tilt downward. The top of the plate 95 is faced with a cushion 100 which may be a rubber disk. Said cushion engaging the bottom 30 of the receptacle, the same being corrugated to prevent slippage. 90

The object of the last described parts is to raise the rearmost receptacle 29 a sufficient distance so that it will clear a stop plate 101 located at the rear end of the compartment in which said receptacle is carried, the receptacle being elevated high enough to be taken up by the receiving device at the station. This action is controlled by the movement of the cross bar 75 through the rod 80 and the parts connected to the rear end of the latter. The receptacle will be elevated on the forward movement of the cross bar 75, and a new receptacle is pushed into the compartment on the rearward movement of the cross bar as hereinbefore described. To 100 actuate these devices as the car reaches a station, the box-like structure 39 is employed. After the forward portion of the car has passed under the box and removed the receptacle suspended therefrom as hereinbefore described, the rear portion of the car passes beneath the box. As the rearmost receptacle 29 is in elevated position, it will be seen that the rollers 33 will have entered the box, the bracket member 32 entering the 110 bottom slit 40 of the box. A stop is provided to halt the receptacle while the car proceeds on its way. This stop is a plate 115 102 which is pivoted at 103 to swing in a horizontal plane under the box. The pivot 103 is a pin positioned alongside the box and supported by top and bottom bracket members 104 secured, respectively, to the top and bottom of the box. The plate 102 has an arm 105 extending at a right angle 120 therefrom and having connected to its free end a spring 106 anchored to an arm extending from the top bracket member 104. The free end of the plate 102 has a beveled tongue 107. The spring serves to normally 125 130

hold the plate so that the tongue spans the slit 40. The plate readily yields to allow the removal from the box of the receptacle to be delivered to the car. The roof of each compartment 16 and 17 has a longitudinal abutment 108 which is in line with the side of the plate 102, the latter in its normal position extending obliquely from the box. Thus when the rear portion of the car is about to pass out from under the box, the abutment strikes the slanting side of the plate and gradually forces said plate inward under the box until the angle at the junction of the plate and its tongue 107 spans the slit 40. The plate now acts as a stop for the receptacle which has been deposited in the box by engaging the bracket member 32 thereof, and allows the car to proceed, while holding the delivered receptacle in check. At the next station, the operation is repeated, a receptacle being delivered and a waiting one collected.

The car is suspended from an overhead cable 109 supported by the bracket arm 42, and similar arms at intervals along the route. Between the flanges 44 of the bracket arm seats a cable clamping means comprising two L-shaped members 013 and 014, respectively, positioned on the arm 42 between the flanges 44, and secured by a bolt 015. The members are so placed that one of the flanges of each is upstanding and the other flanges horizontal, the horizontal flange of one member seating on the corresponding flange of the other member and having a slot 016 through which the bolt 015 passes. The upstanding flanges are spaced and between the same is held a cable clamp 017, a bolt 018 passing through the shank 40 of the clamp and the upstanding flanges.

On the cable 109 are mounted two propelling trucks or cars 019 from which the hereinbefore described car is suspended at its front and rear ends by hangers 020, the latter being connected to the middle compartment 15. The trucks 019 are propelled by electric motors suitably geared to the wheels thereof as shown and described in applicant's Patent No. 1122785, dated December 50 29, 1914.

The hangers 020 pass through the roof of the compartment 15 into the latter, the portions of the hangers which are in the compartment being reduced in diameter and shaped to form a spindle 021. The spindle of the front hanger is journaled in a housing or bearing 022 secured to the inner face of the front wall of the compartment 15. On the bottom of the spindle is an abutment 023 which engages the bottom of the housing and prevents the spindle from being withdrawn upward. The housing has a vertical slit 024 registering with a slit 72 to accommodate the pitman 71. It will be noted that 65 the spindle and its bearing or housing are

located slightly off the longitudinal center line of the compartment 15 so as not to interfere with the pitman. The spindle of the rear hanger is supported in the same manner as the forward spindle, its bearing or 70 housing being mounted on the rear wall of the compartment. The spindles provide a swiveling connection between the car and the propelling trucks 019, and the latter are therefore enabled to round curves.

The bottom of the car is open except as braced by channel bars 025. These bars support two laterally spaced guide rails 026 located at the center of the car and running in the direction of the length thereof. 80 The rails diverge at their forward ends, as indicated at 027. These rails operate in connection with idlers 028 to guide the car, said idlers being supported from the poles 43 by means of bracket arms 029. As the car 85 approaches the idler, the latter enters between the flared ends of the rails and in passing along the parallel portions of the same steadies the car if it should be swaying sidewise. The idlers will be so positioned that they come between the parallel portions of the rails before delivery or collection of the receptacles commences.

The box 39 is also provided with pivoted dogs 030 similar to the dogs 36, for preventing a delivered receptacle from backing out.

The rear ends of the side walls of the compartments 16 and 17 have bulges 031 so that the removal of the receptacle 29 may be effected by hand.

The two side compartments 16 and 17 are provided in order that a collection and delivery may be made at either side of the overhead track or cableway 109. Inasmuch as the rearmost receptacle 29 of each compartment 16 and 17 is elevated for delivery, the stations along the route will be located alternately on opposite sides thereof. Therefore, although both receptacles are elevated, only one will be delivered, the one which 105 comes in line with the delivery apparatus being taken from the car. The compartments are designed to hold a number of receptacles corresponding to the number of stations along the route, as otherwise the receptacles collected along the route will be delivered again before the end of the route is reached.

The function of the light spring 84 is to cushion the movement of the rod 80, whereas the function of the heavy spring 85 is to give a more responsive or quicker movement to the parts when the receptacle is to be lifted.

I claim:

1. In a delivery and collection apparatus, the combination with the receptacles to be delivered and collected, said receptacles having suspension means capable of a sliding movement; of a car having a longitudinal 130

compartment in which the receptacles are suspended in a row, a support for the receptacles to be collected and discharged, a track on which the car is mounted for travel, propelling means for the car, means for discharging the rearmost one of the receptacles in the car, said discharging means including a lifter for elevating the receptacle into position to be taken up by the aforesaid support, 5 means for collecting a receptacle, said collected receptacle entering the car at its front end, means for advancing the collected receptacle into the car and advancing the other receptacles in the car toward the rear end 10 thereof to place the rearmost one in discharge position, and an operative connection between the aforesaid advancing means and the lifter. 15

2. In a delivery and collection apparatus, 20 the combination with the receptacles to be delivered and collected, said receptacles having suspension means capable of a sliding movement; of a car having a longitudinal compartment in which the receptacles are suspended in a row, a support for the receptacles to be collected, a track on which the car is mounted for travel, propelling means for the car, means for discharging the rearmost one of the receptacles in the car, means 25 for collecting a receptacle, said collected receptacle entering the car at its front end, and means controlled by the discharged receptacle for advancing the collected receptacle into the car and advancing the other receptacles 30 in the car toward the rear end thereof to place the rearmost one in discharge position. 35

3. In a delivery and collection apparatus, 40 the combination with the receptacles to be delivered and collected, said receptacles having suspension means capable of a sliding movement; of a car having a longitudinal compartment in which the receptacles are suspended in a row, a support for the receptacles to be collected, a track on which the 45 car is mounted for travel, propelling means for the car, means for discharging the rearmost one of the receptacles in the car, means for collecting a receptacle, said collected receptacle entering the car at its front end, 50 means for advancing the collected receptacle into the car and advancing the other receptacles in the car toward the rear end thereof to place the rearmost one in discharge position, and a movable member in the path of 55 the discharging receptacle and actuated thereby, said movable member controlling the receptacle advancing means.

4. In a delivery and collection apparatus, 60 the combination with the receptacles to be delivered and collected, said receptacles having suspension means capable of a sliding movement; of a car having a longitudinal compartment in which the receptacles are suspended in a row, a support for the receptacles to be collected and discharged, a track 65 on which the car is mounted for travel, propelling means for the car, means

on which the car is mounted for travel, propelling means for the car, means for discharging the rearmost one of the receptacles in the car, said discharging means including a lifter for elevating the receptacle into position to be taken up by the aforesaid support, a support at the front end of the car for receiving the receptacle to be collected, means for advancing the collected receptacle from said support into the car and advancing the other receptacles in the car toward the rear end thereof to place the rearmost one in discharge position, and an operative connection between the aforesaid advancing means and the lifter. 70 75 80

5. In a delivery and collection apparatus, the combination with the receptacles to be delivered and collected, said receptacles having suspension means capable of a sliding movement; of a car having a longitudinal compartment in which the receptacles are suspended in a row, a support for the receptacles to be collected, a track on which the car is mounted for travel, propelling means for the car, means for discharging the 90 rearmost one of the receptacles in the car, a support at the front end of the car for receiving the receptacle to be collected, and means controlled by the discharged receptacle for advancing the collected receptacle from said support into the car and advancing the other receptacles in the car toward the rear end thereof to place the rearmost one in discharge position. 95

6. In a delivery and collection apparatus, 100 the combination with the receptacles to be delivered and collected, said receptacles having suspension means capable of a sliding movement; of a car having a longitudinal compartment in which the receptacles are suspended in a row, a support for the receptacles to be collected, a track on which the car is mounted for travel, propelling means for the car, means for discharging the rearmost one of the receptacles in the car, a support at the front end of the car for receiving the receptacle to be collected, means for advancing the collected receptacle from said support into the car and advancing the other receptacles in the car toward the rear end 105 thereof to place the rearmost one in discharge position, and a movable member in the path of the discharging receptacle and actuated thereby, said movable member controlling the receptacle advancing means. 110 115 120

7. In a delivery and collection apparatus, the combination with the receptacles to be delivered and collected, said receptacles having suspension means capable of a sliding movement; of a car having a longitudinal compartment in which the receptacles are suspended in a row, a support for the receptacles to be collected and discharged, a track on which the car is mounted for travel, propelling means for the car, means 125 130

for discharging the rearmost one of the receptacles in the car, said discharging means including a lifter for elevating the receptacle into position to be taken up by the 5 aforesaid support, a support at the front end of the car for receiving the receptacle to be collected, a push bar for advancing the collected receptacle from said support into the car and advancing the other receptacles 10 in the car toward the rear end thereof to place the rearmost one in discharge position, and an operative connection between the lifter and the push bar.

8. In a delivery and collection apparatus, 15 the combination with the receptacles to be delivered and collected, said receptacles having suspension means capable of a sliding movement; of a car having a longitudinal compartment in which the receptacles are 20 suspended in a row, a support for the receptacles to be collected, a track on which the car is mounted for travel, propelling means for the car, means for discharging the rearmost one of the receptacles in the 25 car, a support at the front end of the car for receiving the receptacle to be collected, and a push bar controlled by the discharged receptacle for advancing the collected receptacle from said support into the car and 30 advancing the other receptacles in the car toward the rear end thereof to place the rearmost one in discharge position.

9. In a delivery and collection apparatus, 35 the combination with the receptacles to be delivered and collected, said receptacles having suspension means capable of a sliding movement; of a car having a longitudinal compartment in which the receptacles are suspended in a row, a support for the receptacles to be collected, a track on which the car is mounted for travel, propelling means for the car, means for discharging the rearmost one of the receptacles in the 40 car, a support at the front end of the car for receiving the receptacle to be collected, a push bar for advancing the collected receptacle from said support into the car and advancing the other receptacles in the car toward the rear end thereof to place the 45 rearmost one in discharge position, and a movable member in the path of the discharging receptacle and actuated thereby, said movable member controlling the push bar.

50 10. In a delivery and collection apparatus, the combination with the receptacles to be delivered and collected, said receptacles having suspension means capable of a sliding movement; of a car having a longitudinal compartment in which the receptacles are suspended in a row, a support for the receptacles to be collected and discharged, a track on which the car is mounted for travel, propelling means for the car, 55 means for discharging the rearmost one of the

the receptacles in the car, said discharging means including a lifter for elevating the receptacle into position to be taken up by the aforesaid support, a support at the front end of the car for receiving the receptacle 70 to be collected, a push bar for advancing the collected receptacle from said support into the car and advancing the other receptacles in the car toward the rear end thereof to place the rearmost one in discharge position, and an operative connection between the lifter and the push bar.

11. In a delivery and collection apparatus, the combination with the receptacles to be delivered and collected, said receptacles 80 having suspension means capable of a sliding movement; of a car having a longitudinal compartment in which the receptacles are suspended in a row, a support for the receptacles to be collected, a track on which the car is mounted for travel, propelling means for the car, means for discharging the rearmost one of the receptacles in the car, a support at the front end of the car for receiving the receptacle to be collected, 85 a push bar for advancing the collected receptacle from said support into the car and advancing the other receptacles in the car toward the rear end thereof to place the rearmost one in discharge position, a motor carried by the car and operatively connected to the push bar, and motor-controlling means actuated by the discharged receptacle.

12. In a delivery and collection apparatus, the combination with the receptacles to be delivered and collected, said receptacles having suspension means capable of a sliding movement; of a car having a longitudinal compartment in which the receptacles are suspended in a row, a support for the receptacles to be collected and discharged, a track on which the car is mounted for travel, propelling means for the car, means for discharging the rearmost one of the receptacles in the car, said discharging means including a lifter for elevating the receptacle into position to be taken up by the aforesaid support, a support at the front end of the car for receiving the receptacle 100 to be collected, a push bar for advancing the collected receptacle from said support into the car and advancing the other receptacles in the car toward the rear end thereof to place the rearmost one in discharge position, a motor carried by the car and operatively connected to the push bar, and motor-controlling means actuated by the discharged receptacle.

13. In a delivery and collection apparatus, the combination with the receptacles to be delivered and collected, said receptacles having suspension means capable of a sliding movement; of a car having a longitudinal compartment in which the receptacles 105 110 115 120 125 130

are suspended in a row, a support for the receptacles to be collected and discharged, a track on which the car is mounted for travel, propelling means for the car, means for discharging the rearmost one of the receptacles in the car, said discharging means including a lifter for elevating the receptacle into position to be taken up by the aforesaid support, a support at the front 10 end of the car for receiving the receptacle to be collected, a push bar for advancing the collected receptacle from said support into the car and advancing the other receptacles in the car toward the rear end thereof to 15 place the rearmost one in discharge position, a motor carried by the car and operatively connected to the push bar, motor-controlling means actuated by the discharge receptacle, and an operative connection between the lifter and the push bar.

14. In a delivery and collection apparatus, the combination with the receptacles to be delivered and collected, said receptacles having suspension means capable of a sliding movement; of a car having a longitudinal compartment in which the receptacles are suspended in a row, a support for the receptacles to be collected, a track on which the car is mounted for travel, propelling 25 means for the car, means for discharging the rearmost one of the receptacles in the car, a support at the front end of the car for receiving the receptacle to be collected, a push bar for advancing the collected receptacle from said support into the car and advancing the other receptacles in the car toward the rear end thereof to place the rearmost one in discharge position, a motor carried by the car, a wrist wheel driven 30 by the motor, a pitman connection between the wrist wheel and the push bar, and a motor-controlling means actuated by the discharged receptacle.

15. In a delivery and collection apparatus, the combination with the receptacles to be delivered and collected, said receptacles having suspension means capable of a sliding movement; of a car having a longitudinal compartment in which the receptacles 45 are suspended in a row, a support for the receptacles to be collected, a track on which the car is mounted for travel, propelling means for the car, means for discharging the rearmost one of the receptacles in the car, a support at the front end of the car for receiving the receptacle to be collected, a push bar for advancing the collected receptacle from said support into the car, and advancing the other receptacles in the 50 car toward the rear end thereof to place the rearmost one in discharge position, an electric motor carried by the car and operatively connected to the push bar, a switch controlling the motor, and a movable member in the path of the discharging receptacle.

tacle and operatively connected to the switch.

16. In a delivery and collection apparatus, the combination with the receptacles to be delivered and collected, said receptacles 70 having suspension means capable of a sliding movement; of a car having a longitudinal compartment in which the receptacles are suspended in a row, a support for the receptacles to be collected, a track on which the car is mounted for travel, propelling means for the car, means for discharging the rearmost one of the receptacles in the car, a support at the front end of the car for receiving the receptacles to be collected, 75 a push bar for advancing the collected receptacle from said support into the car and advancing the other receptacles in the car toward the rear end thereof to place the rearmost one in discharge position, an electric motor carried by the car, a wrist wheel driven by the motor, a pitman connection between the wrist wheel and the push bar, a switch controlling the motor, a movable member in the path of the discharging receptacle and operatively connected to the switch for closing the same, and switch opening means on the shaft of the wrist wheel.

17. In a delivery and collection apparatus, the combination with the receptacles to be delivered and collected, said receptacles having suspension means capable of a sliding movement; of a car having a longitudinal compartment in which the receptacles 90 are suspended in a row, a support for the receptacles to be collected, and discharged, a track on which the car is mounted for travel, propelling means for the car, means for discharging the rearmost one of the receptacles in the car, said discharging means including a rock shaft for elevating the receptacle into position to be taken up by the aforesaid support, one of the branches of said lever carrying a support engageable 100 with the bottom of the receptacle to be lifted, an actuating rod connected to the other branch of the lever, a support at the front end of the car for receiving the receptacle to be collected, a push bar for advancing the collected receptacle from said support into the car and advancing the other receptacles in the car toward the rear end thereof to place the rearmost one in discharge position, and an operative connection between the aforesaid actuating rod and the push bar.

18. In a delivery and collection apparatus, the combination with the receptacles to be delivered and collected, said receptacles having suspension means capable of a sliding movement; of a car having a longitudinal compartment in which the receptacles are suspended in a row, a support for the receptacles to be collected, a track on which the car is mounted for travel, propelling 125

65 member in the path of the discharging receptacle.

- means for the car, means for discharging the rearmost one of the receptacles in the car, means for collecting a receptacle, said collected receptacle entering the car at its front 5 end, means for advancing the collected receptacle into the car and advancing the other receptacles in the car toward the rear end thereof to place the rearmost one in discharge position, pivoted dogs carried by the 10 car, and holding means carried by the receptacles and engageable by said dogs to prevent forward movement of the receptacles in the compartment.
19. In a delivery and collection apparatus, 15 the combination with the receptacles to be delivered and collected, said receptacles having suspension means capable of a sliding movement; of a car having a longitudinal compartment in which the receptacles are 20 suspended in a row, a receiver for the receptacles to be discharged from the car, a pivoted retaining member for the receptacle on the receiver, means on the car for controlling the retaining member, a track on 25 which the car is mounted for travel, propelling means for the car, means for discharging the rearmost one of the receptacles in the car, a support at the front end of the car for receiving the receptacle to be collected, a push bar for advancing the collected receptacle from said support into the car and advancing the other receptacles in the car toward the rear end thereof to place the rearmost one in discharge position, the aforesaid 30 support at the front end of the car having
- a receptacle passageway leading into the car, and a pivoted dog carried by the push bar and straddling said passageway, said dog yielding to permit the travel of the receptacle along the passageway toward the car, and preventing travel of the receptacle in the opposite direction.
20. In a delivery and collection apparatus, 40 the combination with the receptacles to be delivered and collected, said receptacles having suspension means capable of a sliding movement; of a car having a longitudinal compartment in which the receptacles are 45 suspended in a row, a receiver for the receptacles to be discharged from the car, a pivoted retaining member for the receptacle on the receiver, means on the car for controlling the retaining member, a track on 50 which the car is mounted for travel, propelling means for the car, means for collecting a receptacle, said collected receptacle entering the car at its front end, and means for advancing the collected receptacle into the 55 car and advancing the other receptacles in the car toward the rear end thereof to place the rearmost one in discharge position.

In testimony whereof I affix my signature in presence of two witnesses.

JOSEPH F. MONTINE.
